RAZOR BLADE DISPENSER

Donald M. Genaro, Haworth, N.J., assignor to Philip Morris Incorporated, New York, N.Y., a corporation of Virginia

Filed July 16, 1968, Ser. No. 12,791

Term of patent 14 years

Int. Cl. D9—04

U.S. Cl. D9—224

FIG. 1

FIG. 5

FIG. 2

FIG. 3

FIG. 4

FIGURE 1 is a perspective view of the razor blade dispenser embodying my design.

FIGURE 2 is a top plan view of the razor blade dispenser shown in FIGURE 1.

FIGURE 3 is an elevational view of the razor blade dispenser shown in FIGURES 1 and 2 as viewed from the back side thereof.

FIGURE 4 is a bottom plan view of the razor blade dispenser shown in FIGURES 1 and 2.

FIGURE 5 is an elevational view of the razor blade dispenser as viewed from the rear end thereof.

I claim:

The ornamental design for a razor blade dispenser, as shown.
